UNITED STATES PATENT OFFICE.

PATRICK H. MACK, OF BRADFORD, PENNSYLVANIA, ASSIGNOR TO OIL WELL SUPPLY COMPANY, OF PITTSBURGH, PENNSYLVANIA, A CORPORATION OF PENNSYLVANIA.

OIL-WELL PACKER.

1,350,553.

Specification of Letters Patent. Patented Aug. 24, 1920.

Application filed November 23, 1915. Serial No. 62,962.

To all whom it may concern:

Be it known that I, PATRICK H. MACK, a citizen of the United States, residing at Bradford, in the county of McKean and 5 State of Pennsylvania, have invented certain new and useful Improvements in Oil-Well Packers, of which the following is a specification.

This invention relates to improvements in 10 packing structures and more particularly to structures employed in the packing of wells.

The invention is of the type disclosed in 15 my companion application filed August 31, 1915, Serial No. 48,224, the present invention embodying the general ideas set forth in the said companion application, the disclosure being of a different form of structure for carrying such ideas into effect.

The present invention, like that of the 20 companion application, has for its purpose the establishing of a zone or zones of uniform resistance within the expansible packing by the compressing action of and on the packing. In the present invention, however, the zones are produced by individual 25 expansible members of comparatively small width and of a particular cross section in combination with rigid members which co-operate with the individual expansible members in producing the packing action. This 30 change in construction permits of a material decrease in the cost of production and of substitution of parts in case of re-use of the packer. Furthermore, the zones are 35 more definitely formed and located.

To these and other ends, my invention consists in the improved construction and combination of parts hereinafter fully described, illustrated, and particularly pointed out in 40 the appended claims.

In the accompanying drawing,

Figure 1 is an enlarged sectional view 45 showing a simple arrangement of parts for producing the desired result, the parts being shown in unexpanded position.

Fig. 2 is a similar view showing the packer expanded.

Figs. 3 and 4 are vertical sectional views 50 of various forms of well packers, showing the invention applied thereto.

Fig. 5 is a sectional view showing a modified arrangement.

Referring more particularly to Figs. 1 and 2, 10 represents a tube threaded at one 55 end to receive a compressing member 11.

12 indicates a sectional packing structure formed of two series of sections or members, one series having the sections preferably formed of rubber or other expansible material, and being of two types indicated 60 respectively at 12^a and 12^b, the former being the end sections; the other series is in the form of rigid members presently referred to. The packing structure is located between the compression member 11 and a 65 member 13. Member 13 may be fixed with respect to tube 10 as in Figs. 1 and 2 or may be movable relatively thereto, it being understood that members 11 and 13, in the packing setting operation, are relatively 70 movable axially in order to provide a compressing action on the structure 12.

As shown, members 11 and 13 are preferably provided with annular flanges which form recesses into which the sections 12^a 75 extend.

The sections 12^b are tubular in form and have their opposite sides oppositely inclined to a plane which intersects the section axis at right angles, the greatest width of the 80 section being on its outer periphery, the inclined sides tending to give the section a wedge shape on a cross section intersecting such plane. The sections 12^b are assembled on the tube 10 alternately with rigid members 14 of the opposite series, said members being preferably of metal, these members being ring-shaped with their opposite sides inclined substantially complementary to the inclined sides of adjacent expansible sections, the greatest width of members 14 being on the inner periphery of the members. 85

The sections 12^b adjacent the sections 12^a are separated therefrom by ring shaped members 14^a, these latter members having 90 inclined sides, but differing from members 14 in that the opposite sides are parallel with each other, thus producing a washer-like effect.

The preferred arrangement of the sections 100 12^a and 12^b and members 14 and 14^a, when assembled, is shown in Fig. 1. This arrangement provides a composite structure extending from the member 11 to member 13, the structure having the general shape 105 and appearance of the ordinary packer, with the exception that the outer periphery of members 14 and 14^a will be exposed at the surface of the packer. While the packer has such general appearance, its structure 110

differs radically from that of the ordinary packer, in that it consists of successive layers of expansible and rigid members with the contact faces of the layers relatively arranged to provide a wedge action on the expansible members 12^b when pressure is applied axially of the members. As the members 14 and 14^a are free to move in the direction of length of tube 10, it will be readily understood that the compressing action on members 12^b is distributed throughout the length of the packing, this being especially true by reason of the fact that the sections 12^b are in the form of rings, expansion of which is against the normal tendency to retain the initial shape and size of the rings at their inner peripheries. Consequently, the sections 12^b will be compressed uniformly and will form successive zones of substantially uniform resistance, the two series of sections coöperating to build up the resistance as the compression is applied and as a result of the compressing action.

In Fig. 5, I have shown a modified arrangement, in that the sections 20 are undercut as at 20^a, the rigid members 21 having a face 21^a complementary to the undercut face, the wedge cross section, in this form, having its thin edge at one end of the member instead of at the periphery. The opposite end of the member may have various configurations, as at 21^b, 21^c and 21^d, Fig. 5 showing various ways in which the configuration may be provided.

The fact that the sections are of comparatively narrow width decreases the cost of manufacture, due to the fact that where the rubber packing is continuous and of considerable length (often of a length in excess of eighteen inches), imperfections in manufacture, even though small, form a bar against the use of the packing. Furthermore, the fact that packing members can be built up in any desired length by simply adding or taking away the necessary number of sections and rings, enables the desired size packer to be produced by simply carrying sections and members of the two series in stock, thus dispensing with the necessity of carrying various sizes of the expensive tubular packers heretofore employed. In addition, the fact that this uniformity in resistance is produced and the further fact that this resistance is in the form of individual zones located successively in the direction of flow of leakage, it is possible to provide the desired packing effect by the use of packing structures of less length than that required with the ordinary continuous tubular packing.

As will be readily understood, the general principles of Figs. 1 and 2 may be embodied in various types of packers. For instance, in Fig. 3 I have shown it applied to a packer

of the type disclosed in my companion application, filed March 5, 1915, Serial No. 12,304, the packer in this case being one set solely by rotation of a tool, the form shown being that of a packing plug at the bottom of a well, a location where the plug must retain its position independent of any weight and against the action of pressures. In this form, the packing member is set by the rotation of a threaded stem *a* working in the sleeve *a'*, this action causing the cap *a²* to be moved inwardly to compress the packing, the fixed or opposing member being indicated at *a³*.

In Fig. 4, I have shown the invention of Figs. 1 and 2 as applied to a packer which is adapted to be set by the superimposed weight of the upper sections, the example shown being that of the structure disclosed in the patent to P. H. and F. H. Mack, No. 1,145,155, July 6, 1915. In this arrangement the packing member is set by the weight of the superimposed pipe sections when the lower end of the packer reaches an abutment within the well. In this view, the fixed member is indicated at *b* and the movable member at *b'*.

While I have shown the application of the invention in connection with these two forms only, it will be obvious that it may also be employed in connection with other types of packers.

What I claim is:—

1. In packing structures for wells, a tubular body member, opposing recessed end members carried thereon, an upper expansible member entered in one end member, a lower expansible member entered in the opposite end member, a series of expansible members intermediate the upper and lower expansible members, and a series of rigid members alternating with the intermediate expansible members.

2. In packing structures for wells, a tubular body member, opposing recessed end members carried thereon, an upper expansible member entered in one end member, a lower expansible member entered in the opposite end member, a series of wedge-shaped expansible members intermediate the upper and lower expansible members, and a series of rigid wedge-shaped members alternating with the intermediate expansible members.

3. In a packing structure for wells, a body member, opposing end members carried on the body, an upper expansible member, an adjacent rigid member having inclined parallel faces, a lower expansible member, an adjacent rigid member having inclined parallel faces, a series of expansible members intermediate the said upper and lower expansible members having top and bottom faces inclined from the outer periphery inwardly, and a series of rigid members al-

- ternating with the intermediate expandible members and having top and bottom faces inclined in opposition to the faces of the intermediate members.
5. 4. In packing structures for wells, a tubular body member, a plurality of expandible ring members having top and bottom faces inclined from the outer periphery inwardly, a plurality of rigid ring members 10 alternating with the expandible rings and having top and bottom faces inclined in opposition to the faces of the expandible rings, and opposing end members for exerting pressure on the packing.
15. 5. In packing structures for wells, a tubular member, a packing external of the tubular member and comprising a plurality of expandible ring members wedge - shaped throughout, rigid wedge-shaped ring members 20 interposed between the expandible members, said rigid and expandible members having inclined complementary faces adapted to provide expansive action to form zones of substantially uniform resistance within and in the direction of length of the structure by pressure exerted in the direction of member axis, and means for producing such pressure.
6. In packing structures for wells, a tubular member, a packing external of the tubular member comprising a plurality of expandible ring members wedge - shaped throughout each having its greatest width on its outer periphery, a plurality of rigid wedge-shaped ring members each having its greatest width on its inner periphery, a rigid member between adjacent expandible members, and means for expanding the packing by compression.
- In testimony whereof I affix my signature 40 in presence of two witnesses.

PATRICK H. MACK.
